UNITED STATES PATENT OFFICE.

FRANK CHESTER NORTON, OF SALINA, KANSAS.

SHAVING-BRUSH.

1,315,854.

Specification of Letters Patent. Patented Sept. 9, 1919.

Application filed April 25, 1918. Serial No. 230,755.

To all whom it may concern:

Be it known that I, FRANK CHESTER NORTON, a citizen of the United States, residing at Salina, in the county of Saline and State 5 of Kansas, have invented certain new and useful Improvements in Shaving-Brushes; and I do declare the following to be a full, clear, and exact description of the invention, such as will enable others skilled in the art 10 to which it appertains to make and use the same.

My invention has for its object to provide an extremely simple and inexpensive, yet a highly efficient and convenient shaving 15 brush in the handle of which the soap is carried for projection to the bristles as necessary, the device being particularly well adapted for persons of military pursuit in which it is necessary to carry all articles 20 as compactly as possible.

With the foregoing general object in view, the invention resides in the novel features of construction to be hereinafter fully described and claimed, the descriptive matter 25 being supplemented by the accompanying drawing forming a part of this specification. In this drawing,

Figure 1 is a side elevation of the brush;

Fig. 2 is a central longitudinal section 30 thereof after applying a new pencil or stick of soap;

Fig. 3 is a duplicate of Fig. 2 with the exception that it illustrates the manner in which all of the soap may be used; and

Fig. 4 is a transverse section on the plane 35 of the line 4—4 of Fig. 2.

In the drawing above briefly described, the numeral 1 designates a tubular core of uniform diameter throughout its length, 40 while the numeral 2 indicates a sleeve surrounding said core in spaced relation thereto and forming part of the handle of the brush. The brush bristles 3 have their rear ends 4 cemented or otherwise secured in the 45 space between the core 1 and the sleeve 2 and said bristles preferably abut an end ring 5 secured at its edges to the rear ends of said core and sleeve.

The core 1 snugly receives a stick of soap 50 6 and for the purpose of projecting this soap into the bristles as necessary, a follower 7 and screw cap 8 are provided. The circular wall of the screw cap 8 is threaded on the sleeve 2 and cooperates therewith in 55 forming the handle of the brush, the aforesaid follower 7 being secured at its rear end

to the head of the cap and projecting at its front end into the tubular core 1. This follower is preferably of the tubular construction shown but its front end is closed at 9. 60 to prevent the entrance of soap. The follower in question is received rather snugly in the core 1 and it will be observed that said follower projects beyond the cap so that it is necessary to insert the former before threading the latter on the sleeve 2. By this arrangement, the follower and core 65 form centering means for the cap and insure easy application of the latter.

In operation, a stick 6 is placed in the 70 tubular core 1 and the cap 8 is threaded in place so that it projects said stick a suitable distance into the bristles 3. By wetting these bristles, an adequate lather may be worked up on the face to insure an easy 75 shave, and by threading the cap farther onto the sleeve 2, the soap stick 6 will be advanced farther into the bristles, such operation being necessary as said stick is gradually worn away by use. By reference to Fig. 80 3 it will be observed that the entire stick may be projected into the bristles so that there is no waste whatever and no remaining butt or stump to be removed before the application of a new stick. Suitable non-rusting 85 materials are used in the manufacture of the device and the latter will in every way be highly advantageous, particular emphasis being laid upon the extreme simplicity of the device and the ease with which it may 90 be disassembled for sterilizing or for the application of a new stick of soap.

Since probably the best results are obtained from the exact features shown and described, these features are preferably followed, but within the scope of the invention as claimed, numerous minor changes may well be made. Furthermore, it is to be understood that in some instances shaving 95 powder, paste or the like might well be 100 used instead of a stick of soap.

I claim:

A shaving brush comprising a tubular core open at both ends, a cylindrical sleeve 105 surrounding said core in spaced relation thereto and externally threaded substantially throughout its length, said sleeve and core being of substantially the same length and having their rear ends disposed in the same transverse plane, a transverse end ring 110 joining said rear ends of the core and sleeve, bristles anchored at their rear ends between

said core and sleeve, a soap stick in said core, a cylindrical cap threaded on said sleeve and of a depth substantially equal to the length of said sleeve, said sleeve and 5 cap each forming substantially half of the brush handle, and a central, cylindrical, one piece follower fixedly secured to the closed end of said cap and extending at its front end into said core to project the soap stick

therefrom when said cap is threaded forwardly along said sleeve, said follower extending forwardly beyond said cap for reception in said core to center the former when applying the same to the sleeve.

In testimony whereof I have hereunto set 15 my hand.

FRANK CHESTER NORTON.
